C. J. HENSCHEL,
ELECTRICALLY OPERATED VIBRATORY MOTOR.
APPLICATION FILED FEB. 28, 1919.

1,336,519.

Patented Apr. 13, 1920.

UNITED STATES PATENT OFFICE.

CHARLES J. HENSCHEL, OF BROOKLYN, NEW YORK.

ELECTRICALLY-OPERATED VIBRATORY MOTOR.

1,336,519.

Specification of Letters Patent. Patented Apr. 13, 1920.

Application filed February 28, 1919. Serial No. 279,797.

To all whom it may concern:

Be it known that I, CHARLES J. HENSCHEL, a citizen of the United States, residing at Brooklyn, county of Kings, and State of New York, have invented certain new and useful Improvements in Electrically-Operated Vibratory Motors, of which the following is a full, clear, and concise description.

10 My invention relates to electrically operated motors of the type used in electric bells, interrupters, massaging machines and the like, and in which an armature, mounted upon a pivot or shaft, is caused to vibrate by the attraction and release of an electromagnet.

More particularly stated, I seek to produce an electrically operated vibratory motor especially adapted for actuating a clapper used for striking a gong or the like, practically all of the mechanism of the motor, aside from the clapper and parts immediately associated therewith, being mounted upon a supporting frame, and this frame as 25 a unit being removable bodily with its contents, without disturbing the clapper or the gong.

Reference is made to the accompanying drawing forming a part of this specification, and in which like letters indicate like parts throughout the several figures.

Figure 1 is a side elevation showing the motor mechanism as carried by the frame, this frame being detachably mounted upon 35 a casing plate.

Fig. 2 is an end elevation of the mechanism shown in Fig. 1.

Fig. 3 is a plan view of the same.

Fig. 4 is a perspective of the removable frame used for carrying the various working parts, and in this instance consisting of a single member of sheet metal.

Fig. 5 is a perspective of the armature forming a part of the motor mechanism.

Fig. 6 is a perspective of a coupling key used for facilitating rapidity in connecting the motor mechanism with the clapper and disconnecting the same therefrom.

A casing plate is shown at 7. This plate 50 may be either the top plate or bottom plate of a casing for holding the working parts of the motor.

The casing plate 7 is provided with thickened portions 8, 9, 10, serving the purpose 55 of screw holders.

A frame is shown at 11, and in this in-

stance is made of a single integral member of sheet metal. The frame is provided with ears 12, 13, 14, adapted to fit neatly upon the thickened portions 8, 9, 10. The ears 60 are provided with holes 15, through which screws 16 may be extended into engagement with the thickened portions 8, 9, 10, so as to hold the frame detachably upon the casting member 7.

The frame 11 is provided with a slanting portion 17, and fitted neatly upon the same is a block 18 of insulating material.

A pair of binding posts 19, 20, provided with screws 21, 22 are mounted upon the 70 block 18. Each of these binding posts is substantially L-shaped, and extends crosswise of the block 18 so as to overhang the edge thereof, as shown more particularly in Figs. 1 and 3.

The block 18 is provided with screw holes 23, and is held in position by screws 24 which occupy these holes and extend into engagement with the slanting portion 17 of the frame 11.

Connected with the binding posts 19, 20 are wires 25, 26. The wire 26 leads to a magnet 27, and the wire 25 leads to a metallic plate 28.

Engaging this plate is a contact spring 29, 85 the form of which may be understood from Fig. 3. This contact spring is provided with an elongated straight portion 29^a, a shorter portion 29^b bent to an angle to the portion 29^a, and a still shorter portion 29^c 90 bent into a position parallel to the portion 29^a.

Associated with the magnet 27 is an armature 30, the general form of which is indicated in Fig. 5. The armature carries a 95 buffer pin 31 extending through it as indicated in Fig. 3. The pin 31 is double ended, and is made of insulating material, preferably fiber. It is used for striking the portions 29^a, 29^c of the contact spring, as the 100 armature vibrates.

The armature 30 is mounted upon a pin 33, and is provided with a leaf spring 30^a which, by pressing constantly against the adjacent portion of the magnet 27, serves to 105 retract the armature each time the magnet is deenergized. The pin 33 is supported by a pair of ears 34, integral with the frame 11, and having the form indicated in Fig. 3.

The armature 30 is provided with a slot 110 35, extending a slight distance into one of its edges, as indicated more particularly in

2
Fig. 5. This slot is for the purpose of receiving a pair of lugs 36, carried by a rocking disk 37 and serving as a coupling key.

The rocking disk 37 is mounted upon a 5 rocker shaft 38, which extends through a stuffing box 38^a carried by the casing plate 7. The purpose of the stuffing box is to render waterproof the group of mechanism carried by the frame 11, while leaving the 10 opposite or outer face of the casing plate 7 exposed to the weather. This is particularly desirable when the device is used at sea.

Mounted fixedly upon the shaft 38 is a 15 collar 39, which carries a clapper stem 40. This stem carries a clapper for striking a bell, these two last mentioned parts not being shown.

Sandwiched between two plates 41, 41^a of 20 insulating material is a plate 41^b of metal, and engaging this plate is a contact bar 42, carrying an adjustable contact screw 43. Disposed adjacent this screw and carried by the contact spring 29^a is a contact facing 25 43^a.

A wire 47 leads from the magnet 27 to the plate 41^b. Two screws 45, 46 extend through various plates and other parts, and hold the same in proper relation upon the 30 frame 11. The magnet is provided with the usual insulated wire connection 48, for connecting together the spools of the magnet.

The operation of my device is as follows: 35 The parts being constructed and arranged as shown and as above described, the general operation of the electrical mechanism while in use is the same as in other mechanism of similar construction and action, as heretofore used in this art.

Suppose, now, that the operator wishes to disconnect the electric motor mechanism from the casing plate, say for purposes of inspection or repair.

45 He simply removes the three screws 16, whereupon the sheet metal frame 11, carrying all of the electrical mechanism and practically all mechanical parts except the clapper stem, is thus disconnected entirely from the casing plate 7 and all parts supported thereby.

As may be readily understood from Figs. 5 and 6, the armature 30 is not secured to the rocking disk 37 in any sense, the lugs 36 or 55 coupling key fitting loosely into the slot 35. Hence, whenever the frame 11 is lifted off the casing plate 7, the armature 30 easily leaves the key, so that the stem 38 is not disturbed.

60 To replace the electric mechanism, the frame 11 carrying it is put back in position, care being used to see that the coupling key extends into the slot 35, and the three screws 16 are then replaced.

65 Thus the problem of removing and re-

placing the electric mechanism and parts immediately associated therewith involves nothing more complicated than the removal and replacement of three screws. On this account, the device is rendered fool-proof, as 70 any person who can wield a screw-driver can remove and replace the parts in question without the necessity for disarranging any of the parts carried by the sheet metal frame. 75

I do not limit myself to the precise mechanism shown, as variations therein may be made without departing from the spirit of my invention.

I claim:

1. In a device of the character described, the combination, with a casing and a rocking shaft supported by said casing and extending therethrough, of a coupling key mounted upon said rocking shaft, a frame 85 detachably mounted upon said casing, and an electrically operated motor mechanism carried by said frame and including a vibratory armature, said armature being provided with a slot for fitting it upon said 90 coupling key.

2. A device of the character described, comprising a supporting member having the form of a plate, a shaft extending through said plate and provided with a 95 coupling key having the form of a pair of lugs extending from said shaft, a pivotally mounted armature disposed adjacent said coupling key and provided with a slot into which said coupling key fits loosely in order 100 to facilitate the detachment of said armature from said shaft, and electromagnetic mechanism for rocking said armature.

3. In a device of the character described, the combination of a plate, a shaft journaled 105 upon said plate and free to be rocked, a coupling key carried by said shaft and extending from one end thereof in a direction approximating the direction of the length of the axis of the shaft, a frame detachably 110 mounted upon the plate, electric motor mechanism carried by said frame and including a vibratory armature, said armature having a slot into which said coupling key fits in order to couple the armature to the 115 shaft, said electric motor mechanism being self-contained within said frame and being together therewith as a unit detachable from said plate.

4. The combination of a plate, a shaft extending therethrough and adapted to be rocked, a coupling member carried by said shaft, and an electrically operated self-contained motor mechanism detachably mounted upon said plate, said motor mechanism being provided with a vibratory armature having a portion fashioned into a coupling member mating said first-mentioned coupling members. 120

5. In a device of the character described, 130

the combination of a casing plate, a rocker shaft extending through said casing plate for supporting a swinging clapper, a frame made of a single member of sheet metal, and 5 electrically operated motor self-contained within said frame, the frame and the mechanism carried thereby being as a unit detachable relatively to said casing plate and to said rocker shaft extending therethrough.

10 6. A device of the character described, comprising a casing, a stuffing box carried by said casing, a rocker extending through said stuffing box and supported by said casing, a coupling member carried by said rocker shaft, a frame detachably mounted 15 upon said casing, an electrically operated motor mechanism carried by said frame and including a vibratory armature, and a coupling member for detachably engaging said coupling member carried by said rocker 20 shaft.

CHARLES J. HENSCHEL.
